(57) CLAIM

We claim the ornamental design for a gardening container, as shown and described.

DESCRIPTION

FIG. 1 is a top, front, left side perspective view of a gardening container, showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top, front, right side perspective view thereof;

FIG. 9 is a bottom, front, left side perspective view thereof; and,

FIG. 10 is a bottom, front, right side perspective view thereof. The broken lines in the drawings illustrate portions of the gardening container which form no part of the claimed design.
